UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

OIL-SWITCH.

No. 872,513.

Specification of Letters Patent.

Patented Dec. 3, 1907.

Application filed July 30, 1904, Serial No. 218,908.

To all whom it may concern:

Be it known that I, EDWARD M. HEWLETT, a citizen of the United States, residing at Schenectady, county of Schenectady, State of New York, have invented certain new and useful Improvements in Oil-Switches, of which the following is a specification.

The present invention relates to double throw switches of the type employed in starting alternating current motors, or in other circumstances where a definite sequence of circuit connections is required.

It is well known that in starting alternating current motors by means of a compensator it is necessary to first connect the motor terminals to the compensator through a number of its coils so as to give the motor the proper starting voltage, and subsequently when the motor has speeded up to connect its terminals directly to the supply line. Under such circumstances a double throw switch may be employed to make the necessary connections.

The principal object of the present invention is to provide a novel switch organization which may be easily manipulated to make the circuit connections in the order desired and which will assist in preventing the making of the connections in the wrong order.

To this end, I employ a restraining means which, when allowed to operate, will permit the switch to be thrown from its starting to its running position through its intermediate or open position but will stop the switch in its open position whenever thrown from the running position.

My invention also comprises in combination with an electrically-operated trip an automatic signal which will indicate when the switch has been electrically operated; also certain structural features which are capable of use in various types of switches other than the type herein disclosed.

The various features of the invention will be best understood by reference to the following description taken in connection with the accompanying drawing, and the scope of the invention will be particularly pointed out in the appended claims.

In said drawing, Figure 1 is a side elevation of a double throw three phase oil switch constructed in accordance with my invention, parts being shown in section; Figs. 2 and 3 are diagrams illustrating different po-

sitions of the switch operating mechanism; Fig. 4 is a plan view and Fig. 5 is a diagram of the switch circuits shown in connection with an alternating current motor and a compensator.

Referring in detail to the accompanying drawing, 10 designates the switchboard or other suitable support upon which the switch is mounted. Upon the face of the board is pivotally mounted the operating lever 11 and a locking latch 12 which is adapted to engage a pin 13 on the lever and to be drawn out of engagement by a push pin 14. The switch contact and the principal operating mechanism of the switch are located at the rear of the board and supported in part upon the frame 15 and a slab 16 of insulating material carried thereby. An oil can 17 is secured to the under side of the frame 15 and surrounds the switch contacts which extend from the lower side of the support 16. These contacts comprise in the present instance three fixed contacts 18 and three fixed contacts 19 arranged on opposite sides of three center contacts 20. The center contacts 20 furnish a means of support for three movable L-shaped contacts 21. The outer ends 21^a of the contacts 21 are adapted to engage the spring-pressed fingers 22 of the terminals 18, while the other ends 21^b are adapted to engage like spring-pressed fingers 23 on the contacts 19. The contacts 21 are rigidly connected together by a bar 21^c and constitute the movable element of the switch. The fixed contacts 18, 19 and 20 extend through the slab 16 and are provided at their upper ends with suitable terminals 18', 19' and 20' respectively.

Movement is transmitted from the operating lever 11 on the front of the switchboard 10 to the movable switch element by means of a collapsible connection composed of links 24 and 25 connected at their outer ends to the lever and the bar 21^c respectively, and at their inner ends to cranks 26 27, pivoted to a suitable support on the frame 15. Coiled tension springs 28 connect the outer ends of the cranks 26 and 27 and tend to draw them together to collapse the connection between the lever and the switch element. This connection may be locked against collapse by the toggle 29 extending between the same points as the springs 28 and adapted to be slightly overset to hold

the parts in position. It will be apparent that when thus locked the connection is made rigid and any movement given to the operating lever 11 will be faithfully communicated to the movable element in the switch.

The inner end of the crank 27 is provided with an irregularly notched face which co-operates with the spring-pressed pawl or latch 30 to lock the switch in its various operative positions. The face with which the pawl 30 co-operates comprises two extreme limiting shoulders 31 32 and a central notch 33. Whenever the switch is moved to the open position, which is its middle position, the pawl 30 drops into the notch 33 and securely locks the switch against movement. The switch cannot be moved from this position until the pawl is withdrawn. This is accomplished by means of a pull or release rod 34 which is secured at one end to the pawl 30 and extends through the switchboard to its face where it terminates in a button 35. When the pawl 30 is allowed to act the shoulders 31 and 32 limit the throw of the switch in a manner which will be more fully described hereinafter.

One of the links of the toggle 29 is provided with a T-shaped projection 36 whose outer end extends in the paths of movement of three armatures designated 37, 38 and 39. These armatures are suitably pivoted upon supports extending from the upper side of the slab 16, the ends of the armatures 37 and 39 adjacent to the projection 36 are drawn downward by means of tension springs 40 provided with suitable adjusting screws 41 and the corresponding end of the central armature 38 is provided with a weight 42 which performs a corresponding function. The opposite ends of the armatures are located directly above three trip magnets 43, 44 and 45. The windings of the magnets 43 and 45 are connected each in series with its adjacent switch contact 18 and between said contact and its terminal 18'. These connections are more clearly shown in Fig. 5, in which 46, 47 and 48 designate the supply leads of a three-phase distribution circuit in connection with which the switch hereinbefore described is adapted to be used. These leads are connected to the fixed contacts 18 of the switch by means of the connecting wires 49, 50 and 51, the trip coils 43 and 45 being included in the wires 49 and 51. In this diagram 52 designates a three-phase electric motor whose terminals are connected to the switch contacts 20; and 53 designates a compensator whose coils are connected at intermediate points to the terminals 19 19' of the switch. The compensator is connected in Y, the coils at one end being connected together and at the opposite ends being connected to the leads 46, 47 and 48. The trip magnet 44 is included in an

independent circuit including the manually-operated switch 45^a. For the purpose of indicating when the main switch is automatically tripped an auxiliary switch 46^d together with a lamp 47^a are also included 70 in an independent circuit. The switch 46^d comprises a clip 46^a mounted on a fixed support and a plug 46^b carried upon an arm 46^c extending from one of the links of the locking toggle 29.

In the operation of the main switch, assuming that it has been automatically tripped by energizing any one of the magnets 43, 44 and 45, the parts will be in position illustrated in Fig. 2, that is, the toggle 80 29 will be broken through the agency of the actuating armature 37, 38 or 39, as the case may be, and the connection between the lever 11 and the movable switch element will be collapsed, leaving the operating lever 85 11 in its closed position, that is, in a position to be engaged by the latch 12. With the parts in this position the pawl 30 will be seated in the notch 33 and the switch held open. If now it is desired to start the motor 90 52, the rod 34 is drawn out so as to release the pawl 30, and while thus drawn the operating lever 11 is freed from its latch 12 and drawn outward into the position shown in Fig. 3. The first portion of this movement 95 of the operating lever straightens the toggle 29 and extends the springs 28 thus establishing a rigid connection between the lever and the movable switch element and leaving the springs under strain. The latter portion 100 of the movement throws the contacts 21 into engagement with the fixed contacts 19 thus connecting the motor 52 to the supply leads through the compensator 53. This movement also leaves the pawl 30 in engagement 105 with the shoulder 32 of the crank 27. After the motor has speeded up the switch is thrown into the running position by drawing the operating lever 11 back to the position shown in Fig. 2. Since the connection 110 between the operating lever and the movable element of the switch is maintained rigid throughout this movement the contacts 21 are thrown into engagement with the contacts 18 thus leaving the motor connected 115 directly to the supply leads. In this movement the locking pawl 30 is prevented from dropping into the notch 33 by reason of the length of the side 33^a of the notch being greater than the opposing side thus permitting the pawl to pass clear of the notch under the quick closing movement as will be apparent from the illustration in Fig. 1. From this time on in case of an overload on either side of the system the magnet 43 or 45 will 120 be energized and the switch automatically tripped in the manner hereinbefore described. When the switch is thus automatically tripped the breaking of the toggle 29 forces the plug 46^b of the switch 46^d into engage- 125 130

ment with the clip 46^a thus completing the circuit through the lamp 47^a which is thereby lighted and serves to indicate the condition of the switch.

5 It is obvious that alterations and modifications may be made in the structure herein disclosed without departing from the spirit and scope of my invention. I therefore do not wish to be limited to the specific matter 10 disclosed but aim to cover by the terms of the appended claims all such alterations and modifications.

What I claim as new and desire to secure by Letters Patent of the United States, is,—

15 1. The combination with a switch having its open position between two closed positions and biased to open when closed, of means for automatically tripping the switch to allow it to open, and means for automatically locking the switch in open position when 20 automatically tripped.

2. The combination with a switch having an open position between two closed positions and biased to open when closed, of 25 means for automatically tripping the switch to allow it to open, and means for stopping the switch in its open position when thrown from one of said closed positions and permitting it to pass freely through the open position 30 to said closed position when thrown from the other closed position.

3. The combination with a switch having an open position between two closed positions and biased to open when closed, of 35 mechanical means for stopping the switch in its open position whenever thrown from one closed position and permitting it to pass freely through the open position to said closed position when thrown from the other 40 closed position.

4. The combination of a switchboard, a double throw switch located at the rear thereof, an operating lever therefor mounted on the face of the board, means for locking 45 the switch in its open position, and a release rod therefor extending through the switchboard.

5. An electric switch comprising a movable element, an operating lever, a collapsible 50 connection between said lever and said movable element, a spring tending to collapse said connection, means for locking the parts against collapse, means operative to hold said element in its open position, and means 55 for rendering said holding means inoperative.

6. A double-throw electric switch comprising a movable element having its open position between its closed positions, an operating lever, a collapsible connection between 60 said lever and said movable element, a spring tending to collapse said connection, means for locking the parts against collapse, and means operative when the connection is collapsed to hold the switch element to allow 65 the connection to be drawn out into non-col-

lapsed position by the movement of the lever to operate the switch.

7. An electric switch comprising a movable element, an operating lever, a collapsible connection between said lever and said 70 movable element, a spring tending to collapse said connection, means for locking the parts against collapse, and a latch for holding said movable element when the switch is open to allow the connection to be drawn out 75 into non-collapsed position by the movement of the lever to operate the switch.

8. An electric switch comprising a movable element, an operating lever, pivoted links connected to said movable element and 80 to said operating lever and forming a collapsible connection between said lever and said movable element, a spring tending to collapse said connection, means for locking its parts against collapse, and a latch engaging 85 said connection for holding said movable element when the switch is open to allow the connection to be drawn out into non-collapsed position by the movement of the lever to operate the switch. 90

9. An electric switch comprising a movable element, an operating lever, a crank pivoted at one end to the operating lever, a support for the other end of said crank, a crank pivoted at one end to the movable member 95 and mounted at the other end on said support, a collapsible connection between said cranks, means for locking the parts against collapse, and a latch for engaging one of said cranks to allow the connection to be drawn 100 out into non-collapsed position by the movement of the lever to operate the switch.

10. An electric switch comprising a movable element, an operating lever, a crank pivoted at one end to the operating lever, a support for the other end of said crank, a crank pivoted at one end to the movable member and mounted at the other end on said support, a collapsible connection between said cranks, means for locking the parts against 110 collapse, a latch for engaging one of said cranks to allow the connection to be drawn out into non-collapsed position by the movement of the lever to operate the switch, and means for releasing said latch. 115

11. An electric switch, comprising a movable element, an operating lever, a collapsible connection therebetween, a spring tending to collapse said connection, means for locking the same against collapse, means for restraining the movement of the lever end of the connection when the switch is in closed position, means for tripping the locking means whereby the connection is allowed to collapse and the switch is thereby opened and means for 120 rendering said restraining means inoperative.

12. An electric switch, comprising a movable element, an operating lever, a collapsible connection therebetween, a spring tending to collapse said connection, means for locking 130

- the same against collapse, means for restraining the movement of the lever end of the connection when the switch is in closed position, means responsive to predetermined electrical 5 conditions in the circuit for tripping the locking means, whereby the connection is allowed to collapse and the switch is thereby opened and means for rendering said restraining means inoperative.
- 10 13. An electric switch, comprising operating means adapted to be placed under strain and released to actuate the switch, releasing means therefor, means for automatically locking the switch against movement after 15 being thus actuated, and an operating lever for setting the operating mechanism while the switch remains locked and throwing the switch when unlocked to another operative position.
- 20 14. A double throw electric switch, comprising a horizontal support, coöperating contacts on the under side thereof arranged to break in oil, an operating lever, and operating means located above said support 25 and comprising means for stopping the switch in its open position when thrown from one closed position and permitting it to pass freely through the open position to the said closed position when thrown from the other closed position. 30
15. The combination with a switch having an open position between two closed positions, of a latch, and a coöperating notched surface arranged to lock the switch in its open position when thrown from one closed 35 position and permitting it to pass freely through the open position to said closed position when thrown from the other closed position.
16. The combination with a switch having 40 an open position between two closed positions, of a latch, and a coöperating surface comprising a central notch having sides of unequal length whereby the latch will engage the notch to lock the switch in the open 45 position when the switch is thrown in one direction and will ride freely over said notch to permit the switch to pass from one closed position to the other when thrown in the opposite direction. 50

In witness whereof, I have hereunto set my hand this 28th day of July, 1904.

EDWARD M. HEWLETT.
